UNITED STATES PATENT OFFICE.

LOCKE A. SPRAGUE, OF MILWAUKEE, WISCONSIN, ASSIGNOR TO THOMAS A. SPRAGUE, OF DETROIT, MICHIGAN.

ROTARY PUMP.

Application filed August 27, 1923. Serial No. 659,627.

The application relates to rotary pumps and has among its objects the provision of a rotary pump having an unbroken surface with which the bucket blades contact, thereby securing less and more evenly distributed wear; the provision of a rotary pump in which the casing for the rotor comprises a main section which has a chamber for the rotor and a bifurcated passageway, and 10 sections each of which has a passageway connecting into the chamber and also into one of the branch passageways of the bifurcated passageway; the provision of a rotary pump having a liner provided with eccentric inner and outer cylindrical walls; the provision of an eccentric liner which is rotatably adjustable to secure the liquid seal between the buckets and the liner and to re-establish this seal in case of wear of the liner; the provision of a rotary pump having shrouds at the ends of the pockets in the rotor for increasing the distance between the open portions of the adjacent pockets along the surfaces of contact between the rotor ends and the end heads and consequently decreasing the leakage passing between such points; and the provision of a rotary pump in which the buckets are fixedly secured to pins, which latter are rotatably mounted in the rotor, the arrangement being such that increased life of the pump is secured and at the same time endwise movement of the pins with consequent contact with and scoring of the cylinder heads is prevented. Other objects of the invention and serving to decrease the leakage passing between the open portions of the adjacent means for predeterminedly adjusting one of the pockets. With this arrangement, the life of the cylinder heads relative to the cylinder of the rotary pump is increased by reason to provide a predetermined clearance between the cylinder head and the adjacent bearing and furthermore the bucket pins of the bucket pins rotating in the larger end of the rotor and also in the novel features of construction and combinations of parts as will more fully hereinafter appear, relative to the buckets.

In the drawings:

Figure 1 is a sectional end elevation of a rotary pump embodying my invention; Figure 2 is a sectional plan view thereof; Figure 3 is a cross section on the line 3-3 of Figure 1; Figure 4 is an end view of a portion of a modified construction of rotary pump with a cylinder head removed. The casing of the rotary pump comprises the main section or cylinder 1 and the end sections or cylinder heads 2 and 3 secured to the ends of the cylinder by the cap bolts 4. The cylinder has the water inlet and outlet passageways 5 and 6 at opposite sides, each being bifurcated to form branch passageways leading to the ends of the cylinder. The cylinder heads 2 and 3 each have reversely curved passageways 7 and 8 connecting respectively into the branch passageways of the inlet passageway 5 and of the outlet passageway 6 and also connecting into the chamber formed within the cylinder and within which the rotor 9 is located. The cross sectional areas and curvatures of the passageways in both the cylinder and cylinder heads are such that the velocity of the water passing through the pump is changed gradually thereby increasing the efficiency of the pump. The rotor 9 is provided with the angularly spaced longitudinally-extending pockets 10 in its periphery in which are engageable the buckets 11 pivotally mounted upon the rotor. Each bucket has the blade 12 and the arms 13 extending from the blade near its opposite ends, these arms having hubs 14 engageable in recesses 15 formed in the rotor near the opposite ends thereof. The hubs 14 are fixedly secured upon the ends of the pin 16 by the key 17, this pin extending through and rotatably mounted in that portion of the rotor between the recesses 15. Shrouds 18 are shrouds at the ends of the pockets 10 and terminating near the blades 12, these shrouds substantially enclosing the arms 13. The shrouds 18 are held from contacting with and scoring of the cylinder heads by the bearing surfaces 19 which may be comparatively cheaply manufactured and which at the same time may be adjusted to form a close fit to maintain the liquid seal; I have provided the liner 18 within the cylinder 1 and having eccentric inner and outer cylindrical walls. This liner is provided with the longitudinally-extending keyways 19 which are engageable in by a key 20 engaging in the keyway 21 in the cylinder, the arrangement

being such that as the inner wall of the liner wears, or for any reason the liquid seal is not secured, the liner can be rotatably adjusted after removing the key to bring another of its keyways into registration with the keyway in the cylinder after which the key can be re-engaged. With this arrangement the liner may also be more easily assembled in the cylinder.

10 Another important feature of my invention resides in providing a number of liners having eccentric inner and outer cylindrical walls, the outer wall in each instance being of the same diameter while the inner wall 15 has a different diameter, the minimum thickness of the liner being the same but its eccentricity being different. With this arrangement the rotary pump, by using different liners, may be adapted to different 20 conditions of speed, capacity and power. A liner having an outer cylindrical wall of the same diameter as that of the liner 18 but having an inner wall of different diameter than that of the liner 18 is indicated by 25 the reference character 22 in Figure 4. This liner 22, as well as the other liners, has the same minimum thickness of wall opposite the key 20 so that only the maximum clearance between the rotor and the inner 30 cylindrical wall of each liner is varied.

The shaft 23 upon which the rotor 9 is secured extends outwardly through the cylinder heads 2 and 3 and is journaled therein. The arrangement of packing and anti-friction bearings in each cylinder head is the 35 same and therefore the arrangement within the cylinder head 3 will be described. 24 is suitable packing surrounding the shaft 23 and surrounded by the smaller cylindrical 40 flange 25 of the cylinder head 3. 26 is a cupshaped gland surrounding the shaft 23 and having a reduced inner end abutting the outer end of the packing 24 for compressing the same and holding it in place. Located 45 within the enlarged end of the gland 26 is the anti-friction bearing 27, the inner race of which is engaged by the shaft 23. 28 is a cover plate secured to the outer end of the gland and surrounding the shaft for 50 inclosing the space within the gland. This gland is telescopically mounted in the main or larger outwardly extending cylindrical flange 29 of the cylinder head and is secured thereto by suitable means such as the cap 55 bolts 30. With this arrangement it will be seen that the gland in each cylinder head carries an anti-friction bearing, supporting the rotor shaft and also compresses and holds the packing surrounding the shaft in 60 place.

For the purpose of predeterminedly adjusting the clearance between the cylinder heads and the ends of the rotor, I have provided means for predeterminedly adjusting the cylinder head 3 relative to the cylinder

1. This comprises the adjusting or set screws 31 threadedly engaging in the cylinder head 3 and adapted to abut against the cylinder 1. These adjusting or set screws preferably having notched heads, the notches of which are engageable in by locking pins 32 upon the cylinder head 3. In assembling the cylinder head 2 is secured permanently in place. The cylinder head 3 is then placed against the end of the cylinder 1 with the gasket ordinarily used therebetween removed. The adjusting or set screws are next turned until they abut the cylinder, after which each is turned a sufficient distance to permit of the entrance of its locking pin into the succeeding notch in its head. The cylinder head is then removed and the gasket 33 applied to the end of the cylinder after which the cylinder head is again applied and tightened in place by the cap bolts 4 until the adjusting or set screws abut against the cylinder head, the packing being compressible to permit of the necessary movement of the cylinder head toward the cylinder. This provides a predetermined clearance between the cylinder heads and the ends of the rotor.

For the purpose of providing buckets in which the portions engageable with the liner can be easily replaced in case of wear and also for the purpose of providing buckets offering less friction and having better wear resisting qualities than the materials suitable for the main portions of the buckets, I provide the buckets with detachable tips 34 preferably formed of lignum vitae, this material having good lubricating properties, being non-corrosive and performing satisfactorily under high bearing pressures.

What I claim as my invention is:

1. In a rotary pump, the combination with the rotor provided with longitudinally-extending pockets in its periphery and shrouds at the ends of said pockets, of a bucket engageable in each of said pockets, each of the said buckets having an arm portion substantially entirely enclosed by its respective shroud.

2. In a rotary pump, the combination with the rotor provided with longitudinally-extending pockets in its periphery, of buckets pivotally mounted upon said rotor and engageable in said pockets and integral shrouds upon said rotor and at the ends of said pockets, said shrouds partially inclosing said buckets.

3. In a rotary pump, the combination with the rotor provided with a longitudinally-extending pocket in its periphery having recesses near its opposite ends and with shrouds between said recesses and the rotor ends, of a pin rotatably mounted in said rotor and having its ends extending into said recesses, and a bucket engageable in said pocket and having arms extending into

- said recesses and detachably secured upon the ends of said pin.
4. In a rotary pump, the combination with the rotor, of a casing comprising a cylinder surrounding said rotor and cylinder heads detachably secured to said cylinder and carrying said rotor, and means for predeterminedly adjusting one of said cylinder heads relative to said cylinder to provide clearance between said cylinder head and the adjacent ends of said rotor.
5. In a rotary pump the combination with a rotor, of a casing comprising a main section formed with a rotor chamber opening in opposite ends of said section, said section being further formed with an inlet and an outlet passage at opposite sides of the rotor chamber, said passages opening in one of said ends, said casing further comprising an end section journaling said rotor, and having passages, establishing communication between said passages of the main section and the rotor chamber.
6. In a rotary pump the combination with a rotor provided with buckets, of a casing formed with a chamber receiving said rotor and having supply and delivery passages opening endwise into said rotor chamber, and a liner for said chamber rotatively adjustable therein and having its opening ec-
- centric to its outer wall, the said liner forming a bearing for said buckets.
7. In a rotor pump, the combination with a rotor and a cylinder chambered to receive said rotor, of a liner fitted within said chamber having its rotor receiving opening eccentric to its outer wall, and means including a longitudinally extending key for keying said liner to the casing in selective positions of rotative adjustment.
8. In a rotary pump, a rotor formed with a longitudinally extending peripheral pocket, and having a pair of longitudinally aligned recesses opening into said pocket spaced from each other and from the ends of the rotor, a bucket radially movable in said pocket, arms mounting said bucket terminally forming bearings journaled in said recesses, and a pin extending lengthwise through the rotor retaining said bearings in said recesses.
9. In a rotary pump, the combination with a rotor chamber having a longitudinally extending keyway, of an adjustable liner for said chamber, the said liner being provided with a longitudinally extending keyway, and a key engageable in the said keyways for locking the liner within the chamber.

In testimony whereof I affix my signature.

LOCKE A. SPRAGUE.
